UNITED STATES PATENT OFFICE.

RICHARD E. ANDERSON, OF PORTLAND, AND OSCAR G. LARSON, OF SILVERTON, OREGON, ASSIGNORS, BY DIRECT AND MESNE ASSIGNMENTS, TO A. & L. MOTOR CORPORATION, OF ALBANY, OREGON, A CORPORATION OF OREGON.

VALVE MECHANISM FOR INTERNAL-COMBUSTION ENGINES.

Application filed March 8, 1922. Serial No. 542,037.

To all whom it may concern:

Be it known that we, RICHARD E. ANDERSON and OSCAR G. LARSON, citizens of the United States, residing at Portland and Silverton, respectively, in the counties of Multnomah and Marion, respectively, and State of Oregon, have invented certain new and useful Improvements in Valve Mechanisms for Internal-Combustion Engines, of which the following is a specification, reference being had to the accompanying drawings.

This invention relates to the valves of internal combustion engines, and particularly to "valve in the head" motors or engines.

The general object of this invention is to provide an improved valve or valve actuating mechanism for internal combustion engines which will do away with the necessity of using springs, increase the valve opening, reduce the necessity of valve grinding, resetting, etc., and secure a faster action and operation of the valve.

A further object is to provide a cylinder head adapted to be disposed in place of the heads ordinarily found on certain classes of internal combustion engines, and so form the head as to provide it with the valves of our improved construction so that this head with the valves may be substituted for the ordinary head and valves found therewith.

Still another object is to provide a construction of this character comprising an internal and an external head, both of these heads being provided with port openings, the heads being so mounted that by suitable mechanism one port opening of one valve may be turned into coincidence with the exhaust port opening of the other valve, and that at another period in the engine operation the inlet port opening of the exterior valve may be turned into coincidence with the inlet port opening of the interior valve, and that on the compression and working strokes the port openings may be turned entirely out of coincidence with each other so as to close exit from and entrance to the cylinder through the port opening.

Another object is to provide improved means for operating these valves and comprising a cam shaft mounted upon the head of the engine block and continuously rotated in one direction by the crank shaft of the engine, this cam shaft carrying a plurality

of cams which, through suitable mechanism, 55 oscillate the several pairs of valves.

A further object is to secure the oscillation of the valves by means of a cross head sliding in guides and connected by links to the arms of the pair of valves, the cam being 60 provided with a peripheral cam rib operatively engaging said sliding cross head to thereby shift the valves.

Other objects have to do with the details of construction and arrangement of parts as 65 will appear more fully hereinafter.

Our invention is illustrated in the accompanying drawings, wherein:—

Figure 1 is a longitudinal vertical section of the upper portion of an engine block 70 showing the valve mechanism therefor, the cams being in elevation;

Figure 2 is a top plan view of the construction illustrated in Figure 1;

Figure 3 is a longitudinal section on the 75 line 3—3 of Figure 1;

Figure 4 is a section on the line 4—4 of Figure 1, one of the valves 15 and one of the valves 17 being in elevation;

Figure 5 is a fragmentary end elevation of 80 the engine block, the shaft 31 being in section;

Figure 6 is a perspective view of the valve 17;

Figure 7 is a perspective view of the 85 valve 15;

Figure 8 is a projection of the cam track 35;

Figure 9 is a fragmentary top plan view of one of the valve operating mechanisms. 90

Referring to these drawings, 10 designates the engine block of any ordinary internal combustion engine. Above each cylinder 11 the head is formed to provide a circular chamber 12 for the reception of a bushing 13. This chamber is smaller than the cylinder 11 and the upper wall 14 of the cylinder 11, therefore, extends beneath the margin of the opening 12. Disposed within the bushing 13 is a cylindrical exterior valve 15 100 which is cup-shaped or open at its lower end and which is provided with a tubular stem 16.

Disposed within the cylindrical valve 15 is a cup-shaped or cylindrical valve 17 which 105 is also open at its lower end. The lower edges of these valves 15 and 17 rest upon the head 14 of the cylinder. The valve 17 is

provided with an upwardly extending stem 18 which is concentric to and disposed within the tubular stem 16 and projects beyond this tubular stem 16. The recess 12 or socket 5 is closed by a head or cap 19 which is held in place by means of the bolts 20, this cap being approximately rectangular in plan view.

The valves 15 and 17 are illustrated in 10 Figures 6 and 7. The valve 17 is formed with ports 21 and 22, (see Figure 3) the port 21 constituting the intake port and the valve 22 the outlet port or exhaust port, these ports being disposed at about an angle of 15 120° with relation to each other. The valve 15 is also provided with an intake port 23 and an exhaust port 24, these ports being disposed at an angle of approximately 120° with relation to each other. The chamber 20 12 is formed with the oppositely disposed intake and exhaust ports 25 and 26 respectively. It will be noted from Figures 1 and 3 that the valves are so arranged that upon a suction stroke of the engine the intake 25 ports 21 and 23 are in register with the intake port 25 of the cylinder and that upon the exhaust stroke the ports 22, 24 and 26 are in alignment, and that upon the compression and firing strokes of the engine the 30 several ports are out of alignment, and particularly that the ports 21 and 22 of valve 17 are entirely out of alignment with the ports 23 and 24 of the valve 15.

In order that this result may be accomplished, the valves 17 and 15 must be oscillated in opposite directions and held in their oscillated positions. To this end, we mount 35 above the engine head 10 the longitudinally extending cam shaft 27. This is driven by 40 any suitable driving means, as for instance a sprocket wheel 28 mounted upon the cam shaft and driven by means of sprocket chain 29, in turn gearing with a pulley 30 or sprocket wheel mounted upon the cam shaft 45 31 of the engine. This shaft 27 is supported at suitable intervals in upwardly extending brackets 32 of any suitable construction and having bearings within which the cam shaft operates. Mounted upon this 50 cam shaft are a plurality of cams, each cam comprising a wheel-like member 33 having a rim 34, the periphery of this rim being provided with a cam rib 35. This cam rib 35 is irregularly sinusoidal with relation to 55 a line α coincident with the middle plane of the rim 34 and the cam track is shown projected in Figure 8.

Disposed below each cam 33 and above the water space 36 which intervenes between 60 the valve chambers 12, and which water space is connected to the usual water circulating system of the engine, is a cross head guide comprising a plate 37 having apertures whereby it may be attached to the cylinder head by means of screws, whose heads 65

are counter-sunk and have upwardly extending side walls provided with screw holes. Strips 38 are applied to the upwardly extending side walls of the cross head guide and held in place by means of screws 39, 70 these strips overhanging the central channel 40.

Disposed in this central guide channel 40 is a reciprocating cross head 41 having a central bore through which is disposed the 75 lower end of a shouldered pin 42, the upper end of which carries a head 43, this head, as illustrated in Figure 9, being formed with a diametrically extending notch or recess 44, the opposite walls of which are convexly 80 curved with relation to each other. The cam rib 35 fits between these walls 44, and as the cam revolves the sinuous cam rib will cause the cross head 41 to shift longitudinally in the cross head guide 37. 85

Attached to the squared upper end of the stem 18 of valve 17 is an arm 45, and attached to the upper end of the tubular stem 16 is an arm 46, these arms actuating the 90 separate valve cylinders. Pivotedly connected to the pin 42 above the cross head 41 and below the head 43 are links 47, which in turn are pivotally connected to the outer ends of the arms 45 and 46. It will thus be 95 obvious that as the cross head is reciprocated in one direction or the other that the arms 45 and 46 will be shifted from a position in alignment with each other to a position at an angle to each other and extending 100 toward one end of the engine or into an angular position with relation to each other and extending toward the opposite end of the engine. Three positions of these arms are illustrated in Figure 2 and three positions of the several cams are illustrated in 105 Fig. 1.

The cam track 35 is illustrated as a rib, has one-half of its length in approximate coincidence with the median line α of the wheel 34 (Figure 8). One-quarter of this 110 cam track bows toward the right, the other quarter bows toward the left. It follows, therefore, that as the cam revolves that for one-half the revolution of the cam the valves will be held in closed position and 115 that this covers the period of the compression stroke and of the firing stroke. During the next succeeding quarter of the rotation of the cam, the exhaust ports will be 120 open and in communication with the interior of the cylinder, and during the next succeeding quarter of the travel of the cam the valves will be shifted to a position so 125 that the intake ports are in coincidence with each other and with the intake port of the cylinder. Of course, it will be obvious that each cylinder will be timed differently from any other cylinder so that while one cylinder is firing, another cylinder is exhausting, another cylinder is taking in a charge, and 130

in another cylinder the charge is being compressed. The exact timing of each pair of valves will, therefore, be controlled by adjusting the appropriate cam with relation to the cam shaft.

Preferably the cam wheels 34 are locked in place upon the cam shaft by means of keys so that there is no necessity of adjustment, but it is obvious that the mechanism 10 may be constructed so as to secure adjustment of the several cams. The timing of the engine is to be the same as any accepted type of four-cycle combustion engine. The double action of the cam opens and closes 15 the ports on opposite sides of the valves. Opening of the valves for the intake stroke follows the opening of the valves for the exhaust stroke, and the valves stand at rest or closed with relation to each other over 20 the next two strokes, that is the compression and power strokes. The right hand convexity of the cam rib causes the valves to shift to their exhaust position and the left hand curvature or convexity of the rib 25 causes the valves to swing to the intake position. The cams may be placed on the cam shaft, of course, in relation to any desired firing order of the cylinder.

Preferably the cam shaft carries a ball 30 race or any efficient thrust bearing at each end to allow for the thrust from the cams. The gland 19 is forced down on the rim of bushing 13 so as to leave a working fit between the gland and the top of the valve 15. 35 This also provides means to take up wear on the valve bottom and top by removing the gland and bushing and dressing the necessary amount from the top of the bushing. The cylinder head is placed over the engine, 40 as in general practice, but preferably so that the axes of the valves 15 and 17 are coincident with the vertical axis of the cylinder. The cam shaft may be driven by either a silent sprocket chain or by miter 45 or bevel gears or any other suitable means provided a reduction of two to one is secured, that is that the cam shaft 27 shall rotate at half the crank shaft speed, and it is obvious that the cam shaft can be driven 50 either from the front or the rear of the engine. Preferably the cams, the slide or cross head, the links, and the arms 45 and 46 are disposed within a housing and run in a bath of oil. The valves are to be lubricated 55 by oil holes extending through the gland and the outer valve. The cylinder head will be bolted on the engine block in the same manner as any other head is bolted.

It will be seen that the valve for each 60 cylinder comprises two sleeves of cylindrical shape and operating within each other. Both of these cylinders are closed at their upper ends and the inner sleeve, it will be seen, provides a combustion chamber within each valve, and when the sleeves are first

used and are thoroughly clean there is a slight leakage in all probability, but when the engine has been running for about twenty minutes small particles of carbon will collect and will help to seat the valves 70 perfectly. In other words, carbon formation seizes the port edges and valve bottoms to prevent leakage.

It is to be understood that engines may be constructed with these valves initially 75 in place thereon or cylinder heads may be formed with the valves thereon which may be substituted for the ordinary cylinder heads and valve mechanisms commonly found on motor engines. We do not wish 80 to be limited to the details of construction, as it is obvious that these may be varied in many ways without departing from the spirit of the invention.

We claim:

1. In an internal combustion engine, a cylinder having a port opening in its upper end, the axis of the port opening being approximately coincident with the axis of the cylinder, the cylinder being formed to provide a cylindrical chamber above the head of the cylinder concentric to the axis of the port opening, said chamber having an inlet port and an exhaust port, a pair of concentric sleeves disposed in said chamber 95 axially concentric to the axis of said port, each sleeve having a pair of port openings, and crank shaft operated means for oscillating said sleeves to bring their port openings into or out of register with the port 100 openings in the chamber.

2. In an internal combustion engine, a cylinder having a port opening in its upper end and formed to provide a cylindrical chamber concentric to the axis of said port 105 opening and having an inlet port and an exhaust port, a pair of concentric sleeves disposed in said chamber, each sleeve having a pair of port openings, a cam shaft mounted above the cylinder and having a cam thereon, and cam operated means for shifting the sleeves coincidentally in opposite directions to bring their port openings into or out of coincidence with each other and with the port opening of the chamber. 115

3. In an internal combustion engine, a cylinder, a chamber formed above the inner end of the cylinder, concentric hollow sleeves closed at their upper ends, the inner cylinder opening at its inner end into 120 the interior of the cylinder, said sleeves being formed with concentric stems, each of said sleeves having an inlet port and an exhaust port, and the chamber being formed with diametrically disposed inlet and exhaust ports, and engine operated means for oscillating said sleeves to bring their ports into or out of coincidence with each other and into or out of coincidence with the ports of the chamber. 130

4. In an internal combustion engine, a cylinder, a chamber formed above the inner end of the chamber, concentric hollow sleeves closed at their upper ends, the inner cylinder opening at its inner end into the interior of the cylinder, said sleeves being formed with concentric stems, each of said sleeves having an inlet port and an exhaust port, and the chamber being formed with diametrically disposed inlet and exhaust ports, the stems of said valves extending beyond the chamber and one of said stems being longer than the other, an arm mounted upon each stem, an engine driven cam mounted above the cylinder, and means operatively engaging the cam and the arms for giving an oscillating movement to said arms to carry the ports of the sleeves into or out of coincidence with each other and into or out of coincidence with the ports of the chamber.

5. In an internal combustion engine, a cylinder, a chamber formed above the inner end of the chamber, concentric hollow sleeves closed at their upper ends, the inner cylinder opening at its inner end into the interior of the cylinder, said sleeves being formed with concentric stems, each of said sleeves having an inlet port and an exhaust port, and the chamber being formed with diametrically disposed inlet and exhaust ports, the stems of said valves extending beyond the chamber and one of said stems being longer than the other, an arm mounted upon each stem, an engine driven cam mounted above the cylinder, a longitudinally movable slide mounted upon the cylinder head, and links connecting said slide with the extremities of the arms, said cam operating on the slide to cause its reciprocation and the oscillation of said arms.

6. An internal combustion engine including a cylinder having a port opening in its upper end and a chamber above said port opening, an inner cylindrical sleeve closed at its upper end and opening to said port opening at its lower end, an outer concentric sleeve, the chamber being provided with oppositely disposed intake and exhaust openings and each sleeve being provided with an intake and an exhaust opening, the sleeve being also provided with concentric stems, an arm mounted on each stem, a slide carried upon the engine block and shiftable toward or from the stems, links pivotally connecting said slide to the arms, the slide having a head and an engine driven cam mounted above the head, the periphery of the cam being provided with a cam track with which the head engages whereby to cause a reciprocation of the slide and an oscillation of the sleeves in opposite directions to bring their ports into or out of coincidence with each other and with the ports in the chamber.

7. In an engine, a cylinder having a port opening in its upper end and a cylindrical

chamber formed above the cylinder and larger in diameter than the port opening, a bushing disposed within the cylinder, concentric hollow cylindrical sleeves disposed within the bushing, the inner sleeve having an internal diameter approximately equal to the diameter of the port opening into the cylinder, both of said sleeves being closed at their upper ends and being provided with concentric stems, the chamber being formed with diametrically disposed exhaust and inlet ports and the sleeves being each formed with an inlet and exhaust port, a gland closing the upper end of the chamber and normally resting upon the upper end of the bushing, means for adjusting the gland against the bushing, and engine operated means for oscillating said sleeves to bring their ports into or out of coincidence with each other and into or out of coincidence with the ports of the chamber.

8. In an engine of the character described, a cylinder having an axially disposed port at its upper end and a chamber formed above said port, the chamber being cylindrical and concentric to the axis of the cylinder, a bushing disposed within the chamber, concentric cylindrical hollow sleeves disposed within the bushing and resting at their lower ends upon the upper end of the cylinder, the internal diameter of the inner valve being approximately equal to the diameter of the opening in the upper end of the cylinder, said sleeves having concentric stems, a gland surrounding the stems and closing the upper end of the chamber, a cam shaft mounted above the cylinder, a cam carried thereby, and means operated by the cam for oscillating the sleeves in opposite directions to bring their ports into or out of coincidence with each other and the ports of the chamber.

9. In an internal combustion engine, a cylinder, rotary sleeve valves controlling the admission to or exhaust from the cylinder, said valves being concentric and having concentric stems, an arm mounted on each stem and extending in opposite directions, a cross head guide mounted upon the head of the cylinder, a cross head sliding in said guide toward or from the stems of the valve sleeves and having a head, links pivotally connected to the head and to the ends of said arms, and a cam disposed in a vertical plane and operated by the engine, the cam having a sinuous cam track with which the head of the cross head engages.

10. In an internal combustion engine, a cylinder, rotary sleeve valves controlling the admission to or exhaust from the cylinder, said valves being concentric and having concentric stems, an arm mounted on each stem and extending in opposite directions, a cross head guide mounted upon the head of the cylinder, a cross head sliding in said guide

5 toward or from the stems of the valve sleeves and having a head, links pivotally connected to the head and to the ends of said arms, and a cam disposed in a vertical plane and operated by the engine, the cam having a sinuous cam track with which the head of the cross head engages the cam track for a portion of its length being disposed in a single plane for the entire portion of its length and being 10 outwardly bowed toward one side of the cam and for another portion of its length being oppositely bowed.

11. An internal combustion engine having a plurality of cylinders, each cylinder having a port opening in its upper end, the cylinder head having chambers formed in it concentric to the axis of each cylinder, a pair of hollow valve sleeves disposed in each chamber and concentric to the axis of the cylinder and having concentric stems, the chamber being formed with inlet and exhaust openings and the valve sleeves being each formed with an inlet and exhaust opening, a gland closing the upper end of each chamber 25 and surrounding the stems, a longitudinally extending cam shaft mounted upon the engine head and carrying a plurality of cams, one for each cylinder, means actuated by the cams for oscillating the valve sleeves of each 30 pair in opposite directions to bring their ports into or out of coincidence with each other and the ports of said chamber, and means for driving the cams from the cam shaft of the engine.

35 12. In an internal combustion engine, an engine block having a series of cylinders,

each having a port opening at its upper end, a cylinder head adapted to extend over the entire engine block, each head being formed with a cylindrical chamber disposed immediately above the port opening of its corresponding cylinder and larger than said port opening, a bushing disposed in each chamber, hollow, cylindrical, concentric valve sleeves disposed within each bushing, the inner valve sleeve opening into the corresponding cylinder port, each of said valve sleeves being provided with concentric stems, each valve sleeve having an inlet port and an exhaust port and the chamber being formed 50 with inlet and exhaust ports, glands closing the upper ends of the chambers and surrounding the valve stems, a plurality of cross head guides mounted upon the head, one for each cylinder, a cross head slidable in each guide and having an upwardly extending pin formed with a head, arms on the stems of each pair of sleeves, links connecting the ends of each pair of arms with the corresponding pin on the cross head, a cam shaft 55 extending longitudinally of the engine head, a plurality of cams mounted upon the cam shaft and having peripheral cam tracks engaging the heads of the pins on the several cross heads, and means whereby the cam shaft may be actuated by the crank shaft 60 of the engine.

In testimony whereof we hereunto affix our signatures.

RICHARD E. ANDERSON.
OSCAR G. LARSON.
